UNITED STATES PATENT OFFICE.

JAMES HOYT BROWN, OF NEW YORK, N. Y.

SHELL FRAME FOR EYEGLASSES.

Application filed April 9, 1920. Serial No. 372,402.

To all whom it may concern:

Be it known that I, JAMES HOYT BROWN, a citizen of the United States, residing in the city of New York, county and State of New York, have invented a new and useful Improvement in Shell Frames for Eye-glasses, of which the following is a specification.

This invention relates to so-called zylonite or composition shell frames for eye glasses.

The composition shell is usually U-shaped in cross section and fits over and around the eye wire or lens-frame.

A great deal of difficulty has been encountered in securing the composition covering on the eye wire, as the composition tends to shrink or get unshapely.

I have devised a novel and inexpensive method of securing the composition to the eye-wire and my invention resides in said method as well as in the product resulting therefrom.

The accompanying drawing illustrates the preferred embodiment of my invention, it being understood that changes in the same may be made within the scope of the claims and as indicated by the variations thereof.

In said drawing:—

Figure 1, is a view partly in elevation and partly in section of the improved mounting.

Figure 2 is an enlarged perspective view.

Figure 3 is a cross section on the line 3—3 of Figure 1.

Figure 4 is a section like Figure 3, but showing a modification.

Like reference numerals indicate corresponding parts in the different figures of the drawing.

The numeral 1 indicates the eye-wire or frame which is grooved as indicated at 5 to retain the lens.

The zylonite or composition shell is crescent-shape in cross section to cover the eye-wire.

Various more or less expensive and cumbersome means of securing the composition to the eye-wire have been suggested.

I accomplish this result by the following method.

Adjacent the usual end studs 4—4 a lug 2 is struck or swedged from the regular eye-wire 1 thus forcing a sufficient amount of projecting metal above the eye-wire to

permit a hole to be punched or drilled in the said lug 2 as shown in Figure 2. The shell or zylonite rim or casing 3 as before stated is grooved to a size to fit over and perfectly enclose the eye-wire 1 and when on a completed frame, the shell or zylonite covers the metal entirely.

The metal end pieces 4 and the nose bridge (not shown) are preferably not covered with shell or zylonite.

The zylonite covering or casing 3 is cut to the exact length required for a perfect fit to the frame and when it is applied to the frame the lug 2 is forced up into the zylonite thus creating therein a depression as shown in Figure 1. In short, the casing or composition is forced down on to the lug 2 until it fits snug and smooth on the frame.

While in this position holes are drilled or punched through the composition 3 and projecting lug 2. Then a pin or rivit 6 is forced through the composition and held therein by friction. The rivet 6 causes the composition to be doubly locked by reason of the pin and also the lug being forced into the composition. The pin 6 makes a perfect fit to the hole and may be riveted if desired, but this is not at all necessary, due among other things to the fact that there is a tendency of the ends of the zylonite 3 to spring the least particle away from the eye-wire, and this together with the perfect fit of the pin or rivet is sufficient to hold the pin securely in perfect position. There is also a slight tendency of the composition 3 toward longitudinal shrinkage and this is resisted by the pin 6 and lug 2.

Figure 4 is a cut showing the hole through only one side of the zylonite and the pin 6 going into the rear side of the frame. With this construction the pin does not show from the front, yet it holds the composition firmly in place.

What is claimed as new is:—

1. A method of securing a covering on an eye-wire, which consists in forming a lug on the wire, forcing a covering thereover, 100 drilling the covering and lug and placing a pin in the drill hole.

2. An eyeglass frame comprising an eye-wire, a lug thereon, a composition covering fitting the wire and lug and a pin penetrat- 105 ing the lug and covering.

3. An eyeglass frame comprising a ring having lugs thereon, a composition covering pressed onto the lugs, and pins penetrating the composition and the lugs.
- 5 4. In combination, a metallic lens-frame having an eye-wire with connecting end pieces, a non-metallic rim on said frame having its opposite ends on sides of said end pieces, said eye-wire being provided with an outwardly extending boss adjacent 10 each end piece, and an attaching member secured in each boss and extending through the rim.

JAMES HOYT BROWN.
